UNITED STATES PATENT OFFICE

2,438,320

FELT HARDENING MACHINE

William Henry Kingston, Drighlington, Bradford, England, assignor of one-half to William Bywater Limited, Holbeck, Leeds, England, a corporation of Great Britain and Northern Ireland

Original application November 30, 1944, Serial No. 565,985. Divided and this application March 26, 1946, Serial No. 657,288. In Great Britain December 7, 1943

1 Claim. (Cl. 28—14)

1

This invention relates to felt hardening machines of the type comprising a pair of superposed heated tables between which the felt is passed to be compressed and worked in stages by pressure of the upper table and motion which is applied to one or both of the tables. The upper table is raised for the positioning of the felt and then allowed to bear down bodily on to the felt.

Felt hardening machines have the felt passed in stages between the tables (which are usually heated by steam) by a carrier band, on to which the felt is laid in one or more layers from batts suspended to unroll as required. When several superposed layers of felt are treated they may be compressed and worked as a whole into one piece or maintained separate by interposed separating sheets. The felt is submitted to a heat and moisture treatment, e. g., steam, prior to its passage to the tables which harden one section and then succeeding sections of the length of felt as it is passed in stages through the machine. Quite often only the upper table is caused to move for working the felt in one or more directions with a straight and/or circular motion. In one construction both tables have been given a straight line motion in the direction of the length of the table but in opposite directions. To achieve this the lower table is mounted on rocking pedestals.

All the above constructions furnish a more or less smooth action on the felt and it is contended by many people that a more savage action is required to speed up the felting operation and obtain a better felt. A big advantage with a machine having both tables moving is that the felt is worked equally on both sides and with proper motions excellent results can be obtained.

According to the present invention there is provided a felt hardening machine for felting and hardening felt between a pair of superposed flat tables wherein the lower table is supported by means of devices which are capable of affording free movement of the tables in all directions in a substantially horizontal plane, and means for imparting positive motion to at least said lower table in a predetermined manner.

According to a feature of the invention the lower table is supported on pedestals incorporating universal, ball or equivalent joints or bearings.

The invention includes a method of felting the felt in a hardening machine consisting in imparting a rectangular, angular or equivalent curved line motion, circular or elliptical motion to said lower table. These motions may be

2

adapted to have a so-called savage action on the felt.

Referring now to the accompanying drawing in which an embodiment of the invention is shown by way of example only:

Fig. 1 is an end elevation of an improved felt hardening machine;

Fig. 2 is a part sectional enlarged view of one of the universal joints beneath the lower table.

In the embodiment of the invention shown in Figs. 1 and 2, the machine frame 1 is built up in a convenient manner to carry the shafts, gearing and other parts which include four pairs of spaced horizontal brackets 2 on the sides of the frame supporting vertical driving shafts 3. These shafts are driven through other shafts 4, 5, and gearing 6, 7, 8 from an electric motor or other power source in known manner. The upper end of each driving shaft 3 is provided with a device 9 which affords adjustable connection for a vertical driven shaft 10 mounted thereon to be set in or out of vertical alignment with its driving shaft.

A pair of superposed tables 18, 19 which are heated by steam through pipe 20 (or other means), are mounted about the upper level of the machine frame and supported by four pedestals 21 arranged beneath the lower table and constructed to allow the latter free movement in any direction in a substantially horizontal plane. For example, a known form of universal joint comprising two pairs of jaws 22, 23 connected by a pivot member 24 having four trunnions 25 (a ball or equivalent joint, a ball thrust spherical bearing or the like may be used) is provided at the upper and lower end of each pedestal. This universal joint is shown more particularly in Fig. 2 wherein it will be seen the brackets 22 are secured to the underside of the lower table 19 (or the foundation) and the brackets 23 are fixed to the pedestals 21. Each bracket has removable caps 26 coating therewith to house roller bearings 27 which are mounted on to the trunnions 25. The pivot member 24 is simply a separate central body with two pairs of aligned trunnions projecting therefrom at right angles to one another.

The upper table is supported by the lower when pressing upon felt 25 and both tables receive positive motion from the aforesaid driven shafts 10, each of which carries a cam or eccentric. The eccentric arrangement can be achieved by adjusting the shafts 10 out of centre. The cams or eccentrics are mounted in the brackets 29 which are fixed to the two tables and the

upper cams or eccentrics are splined or otherwise mounted to move on the shafts 10 to enable the upper table to be raised and lowered.

The improved felt hardening machine may be modified in various ways particularly in the construction of the motion imparting devices. The feature of the invention is the mounting of the lower table in a manner which enables a variety of motions to be imparted thereto instead of the lower table being limited to straight line motions in opposite directions. Other forms of mountings could be used which would allow movement in any direction in a substantially horizontal plane. In the illustrated construction separate driving shafts 10 are provided for the upper and lower tables but each shaft may operate both tables. The means for raising the upper table may comprise four racks 35, operated by worm gearing 36 and pinions 37 (or other means), which bear up against the upper table as shown, or the cam or eccentric brackets or other parts of the upper table.

This application is a division of my copending application Serial No. 565,985, filed November 30, 1944.

What I claim is:

A felt hardening machine comprising a pair of superposed tables, a plurality of supports on which the lower of said tables is mounted, said supports each comprising a substantially vertically disposed pedestal having universal joints at its upper and lower ends, said pedestals being of such a length that the horizontal movement of the lower table is accompanied by a negligible vertical movement thereof, and means for imparting motion to the lower table.
